ADJUSTABLE GATE

William A. Diefenbronn, St. Louis, Mo.

Application October 12, 1949, Serial No. 120,971

2 Claims. (Cl. 20—71)

1

This invention relates to adjustable gates, and particularly to a gate of this type which may be installed at the top or foot of a stairway, or in a doorway, the principal object of the invention being to preclude accidents to small children. For instance, if installed at the top of a stairway it will protect a small child from injury by falling down the stairs, or if disposed in the doorway of a room a child may safely be left alone in the room without an older person in attendance to see that he does not leave it, and perhaps run into danger. Also, my gate may be positioned in a gateway to keep pet animals from escaping from an enclosure.

One advantage of my device is that it may be adjusted and locked through operation of a single element, that is to say, by merely turning and exerting downward pressure upon said element, this operation serving both to expand the gate to any desired width within its limits of expansion and simultaneously to move its locking mechanism so as to insure its being held at this width. Other features of the invention are its light weight, which permits it to be easily moved from one room to another, the simplicity of its design, which makes for low cost of production, and the fact that ordinary usage will not impair any of its parts.

In the drawings—

Fig. 1 is an elevation illustrating my adjustable gate as it appears with the adjusting mechanism in contracted position.

Fig. 2 is an enlarged detail view (partly broken away) taken on line 2—2, Fig. 1, showing the means for expanding and contracting the gate.

Fig. 3 is an enlarged detail view taken on line 3—3, Fig. 1, showing the means for locking the gate at any desired width.

The invention comprises a frame including upper and lower transverse members 1 and 2, respectively, which are spaced apart any desired distance and secured to vertical side members 3 and 4, respectively. A plurality of vertical, regularly spaced pickets 5 is secured to the upper and lower members 1 and 2, and while in Fig. 1 I have shown only three of such pickets (one being broken away), it is to be understood that there is a sufficient number of the pickets 5 to extend across the gate between the side members 3 and 4. Approximately midway of the upper and lower members 1 and 2 an additional transverse member 6 extends between the vertical members 3 and 4 and is secured thereto.

The transverse members 1 and 6 are provided, respectively, with central apertures 7 and 8 which

2

extend vertically through the members 1 and 6, and a vertical rod 9 extends through and is slideable and rotatable within the apertures 7 and 8. At its upper extremity the rod 9 terminates in a handle 10.

An irregularly shaped element 12 is mounted upon the rod 9, said element having a circular portion 13 provided with a central aperture through which the rod 9 extends, and the rod 9 and element 12 are rigidly secured together by pins 14 which pass through the portion 13 and through the rod 9 (Fig. 2). The irregular element 12 has a pair of oppositely disposed, lateral extensions 15. Each extension 15 is cut out to form a pair of arms 16, and between each pair of arms 15 there is pivotally mounted on a pivot pin 17 a metal strip 18 at one of its ends.

At its opposite end each metal strip 18 is pivotally attached, as at 19, to an elongated member 20 which is slidably positioned within an aperture 21, there being such an aperture 21 in each of the vertical members 3 and 4 of the frame. Each of the elongated members 20 is rigidly attached at its free end to a metal plate 22, and as seen most clearly in Fig. 1, a vertical member 23 is secured by means of screws 24 to the plate 22. The members 23 are shorter than the members 3 and 4, so that their extremities are short of the upper and lower extremities of the members 3 and 4, and since the members 23 contact the door frame when the gate is in operative position, I provide cushioning means 25 of any suitable material at the outer sides of these vertical members.

As shown most clearly in Fig. 1, the lower portion of the rod 9 is provided with ratchet teeth 9^a on one side only. To the underside of the transverse member 6 and opposite the toothed side of the bar 9 I attach an irregularly shaped element 26 which is preferably formed of flat metal. One end of the element 26 is horizontally positioned and secured to the transverse member 6 by means of screws 27. The element 26 is bent downwardly to provide a horizontal section 26^a which is spaced away from the transverse bar 6. Spaced apart from the element 26 and nearer the rod 9 I secure a U-shaped support 28 to the underside of the transverse bar 6 by means of screws 29, and in the channel of the U-shaped support 28 I rest a section 30 of the same flat metal as the element 26, the section 30 being slideable within the channel of the U-shaped support 29. As seen in Fig. 3, the ends of the member 26 and section 30 are spaced apart, and I provide a connecting coil spring 31 therebetween which is secured to

said ends, and retained in position by means of a stop 32 on each of said spaced apart ends. At its free end the section 30 is beveled, as shown at 33, at its upper face and in engagement with the ratchet teeth 9^a of the rod 9.

In operation the procedure is as follows: Suppose the adjustable gate is in its contracted position as shown in Fig. 1 and is to be expanded. This is accomplished by exerting downward pressure on the rod 9 and consequent downward movement of the irregularly shaped element 12 occurs. It will be understood from Fig. 1 that as the element 12 moves down the metal strips 18 gradually approach the horizontal through their pivotal connections 17, and by virtue of the pivotal connections 19 the elongated members 20 are pushed outwardly in the apertures 21. As this movement continues the vertical members 23 are pushed outwardly until they contact the frame of the doorway in which the gate is to be positioned.

It will be remembered that the beveled edge 33 of the element 26 is in engagement with the ratchet teeth 9^a, and due to the peculiar angle of these teeth and of the beveled edge 33, as shown in Fig. 1, the rod 9 may move freely in a downward direction while the gate is being expanded, but is locked against upward movement, so that the gate also is securely locked in its expanded, adjusted position. In order to contract the gate for removal from the doorway, it is necessary to disengage the ratchet teeth and the beveled edge, and this is done by turning the handle 10 and consequently the rod 9, which has the effect of turning the ratchet teeth 9^a away from the beveled edge 33 and presenting the smooth surface of the rod 9 to said beveled edge. The rod 9 may then be drawn upwardly and, as will be readily understood, draws up with it the element 12 and the metal strips 18, which results in drawing the elongated members 20 and the vertical members 23 inwardly, thus reducing the gate to its contracted condition, at which time it can be removed from the doorway.

I claim:

1. An adjustable gate comprising a frame having top, bottom, and side members and pickets secured to said top and bottom members, contact members at the sides of said gate, a transverse member extending across said gate and secured to said side members, said top and transverse members being provided with apertures, a vertical rod slidably and rotatably mounted in said apertures, said side members having apertures and elongated members mounted slidably therein, an element mounted on said vertical rod and having oppositely disposed extensions, connecting strips pivotally secured within said extensions and pivotally secured to said elongated members and adapted to transmit motion from said ver-

tical rod to said contact members; and locking mechanism comprising ratchet teeth on a portion of the surface of the lower end of said vertical rod and a spring-controlled element secured to said transverse member for association with said ratchet teeth, said spring-controlled element having a free end beveled to conform to the inclination of said ratchet teeth so as to prevent upward movement of said vertical rod and to permit downward movement thereof, and said ratchet teeth and said beveled end being capable of disengagement upon rotation of said vertical rod to permit vertical movement of said rod in either direction.

2. An adjustable gate comprising a frame having top, bottom, and side members and pickets secured to said top and bottom members, contact members at the sides of said gate, a transverse member extending across said gate and secured to said side members, said top and transverse members being provided with apertures, a vertical rod slidably and rotatably mounted in said apertures, said side members having apertures and elongated members mounted slidably therein, an irregular element mounted on said vertical rod and having oppositely disposed extensions each of which is cut out to form a pair of arms, a connecting strip pivotally secured between each pair of arms and pivotally secured to one of said elongated members and adapted to translate vertical movement of said vertical rod into horizontal movement of said contact members; and locking mechanism comprising ratchet teeth on a portion of the surface of the lower end of said vertical rod and a spring-controlled element secured to said transverse member for association with said ratchet teeth, said spring-controlled element having a free end beveled to conform to the inclination of said ratchet teeth so as to prevent upward movement of said vertical rod and to permit downward movement thereof, and said ratchet teeth and said beveled end being capable of disengagement upon rotation of said vertical rod to permit vertical movement of said rod in either direction.
